ABSTRACT OF THE DISCLOSURE

A method of recording information on a thermoplastic recording element comprises (1) disposing the thermoplastic surface of the recording element in a solution of charged particles, and (2) electrodepositing, as by electroplating or electrophoresis, the particles from the solution onto only a selected area of the surface, representative of the information, in a quantity corresponding to an average thickness of at least 2×10^{-4} monolayer of deposited particles, but substantially invisible to the naked eye. The recording element with the electrodeposited information thereon may be stored as long as desired, and the information can be made visible, when desired, by (3) charging the surface with a uniform electrostatic charge, and (4) heating the recording element to a temperature at which the thermoplastic material deforms and provides a visible crazed image of the information.

BACKGROUND OF INVENTION

This invention relates generally to the art of electrostatic printing, and more particularly to an improved method of recording information on a thermoplastic recording element. The improved method is particularly useful for recording information economically on a recording element at a relatively high speed in a manner whereby the recording element either may be stored for relatively long periods of time without development or may be developed at will.

It has been proposed to record information on a thermoplastic record element by producing a latent electrostatic image on a layer of thermoplastic material coated with a thin film of substantially incompatible inelastic material. The latent electrostatic image is developed by heating the thermoplastic layer to soften it and to cause the inelastic thin film thereon to craze, whereby to produce a light scattering image of the recorded information. Such a method is described in U.S. Pat. No. 3,317,315, issued to F. H. Nicoll and H. F. Ogawa, on May 2, 1967, for "Electrostatic Printing Method and Element," assigned to the same assignee as the instant invention. While such a prior-art method of electrostatic recording is suitable for many purposes, the recording element cannot be stored for long periods of time without developing the latent electrostatic image thereon. Unless the latent electrostatic image is developed by heating the thermoplastic material of the recording element to provide a crazed image of the information within a relatively short time, the electrostatic charge will decay rapidly and eventually disappear.

In accordance with the improved method of the present invention, information can be recorded on a thermoplastic recording element, at relatively high speeds, and the recording element may be stored for any period of time and developed only when desired.

SUMMARY OF INVENTION

Briefly stated, the improved method of recording information comprises electrodepositing particles, from a solution of charged particles, onto a selected area of the surface of a thermoplastic layer of a recording element.

2

The particles are deposited in a quantity corresponding to an average thickness of at least 2×10^{-4} monolayer of deposited particles, but substantially invisible to the naked eye. The information may be rendered visible subsequently by charging the surface of the recording element and heating the thermoplastic layer to a temperature at which it deforms to provide a visible crazed image at the site of the deposited particles.

In one embodiment of the improved method, the electrodeposition is provided by a current of charged particles that is controlled by photoconductive means. In another embodiment of the improved method, the electrodeposition of the charged particles is controlled by the size of the electrodes and/or modulating pulses applied to the electrodes.

By the terms "electrodepositing" or "electrodeposition," as used herein, is meant the electrical migration of charged particles (ions or charged molecules) in an electric current between electrodes connected to an unidirectional voltage source, as in electroplating or electrophoresis, and depositing the particles adjacent one of the electrodes.

The improved method has the advantage of accepting information on a thermoplastic recording element at relatively high speeds in the form of electrodeposited material so that the recording element may be stored for long periods until such time as it is desired to render the information visible, as by subsequently electrostatically charging and heating the recording element to form a crazed image of the information.

BRIEF DESCRIPTION OF THE DRAWINGS

FIG. 1 is a flow chart of operations in the improved method;

35 FIG. 2 is a cross-sectional view of apparatus, partly schematic, for electrodepositing charged particles, representative of information, on a recording element having a layer of thermoplastic material, in accordance with one embodiment of the improved method;

40 FIG. 3 is a cross-sectional view of apparatus, partly schematic, for electrodepositing charged particles, representative of information, on a recording element having a layer of thermoplastic material that is also photoconductive, in accordance with another embodiment of the improved method;

45 FIG. 4 is a cross-sectional view of apparatus, partly schematic, for recording information on a thermoplastic recording element by electrolytically removing portions of material from a thin film of particles on a thermoplastic layer of a recording element, in accordance with still another embodiment of the improved method; and

50 FIG. 5 is a perspective view, in cross-section, and partly schematic, of apparatus for recording information continuously on a web of a thermoplastic recording element, in accordance with a further embodiment of the improved method.

DESCRIPTION OF THE PREFERRED EMBODIMENTS

60 Referring now to FIG. 1 of the drawings, there is shown a flow chart comprising the operations of the improved method for recording information on a recording element having a thermoplastic layer. In the improved method, the operations are performed upon a recording element that has a thermoplastic layer, either photoconductive or non-photoconductive of the types described in the aforementioned U.S. Pat. No. 3,317,315, or in U.S. Pat. No. 3,291,600, issued to F. H. Nicoll on Dec. 13, 1966, for "Electrophotographic Recording Element and Method of Making."

65 The method of recording information on the recording element comprises disposing the surface of the recording

element in a solution containing charged particles, i.e., ions or charged molecules. The charged particles are electrodeposited from the solution onto one or more selected areas of the surface of the recording element by the process of either electroplating or electrophoresis, depending upon the kind of charged particle employed.

The electrodeposition of the particles on only selected areas of the surface of a recording element, representative of the information, is controlled by varying the resistance to the flow (current) of the particles in the solution between oppositely polarized electrodes. This control may be provided either by photoconductive modulation to vary the electrical conductivity of the current of particles to selected areas of the recording element or by employing electrodes of different sizes in the electroplating or electrophoretic process.

The deposition of particles on a selected area of the surface of the recording element is in a quantity corresponding to an average thickness of at least 2×10^{-4} monolayer of deposited particles, but substantially invisible to the naked eye. This thickness corresponds to 2×10^{11} ions/cm.² or 3×10^{-8} coulombs/cm.². Such minute amounts of deposited particles can be accomplished easily in a matter of a few microseconds. Thus, if the resistance through 1 cm.² of the thermoplastic layer is 10^2 ohms, for example, and the electrodeposition voltage is 10 volts, 10^{-1} amperes of current can flow and 2×10^{11} ions/cm.², the minimum detectable deposit, can be deposited in 3×10^{-7} seconds.

After the information is recorded on the recording element, the recording element may be stored until such time as it is desirable to develop the recorded information to visualize it. The information is visualized by electrostatically charging the surface of the record element with a uniform electrostatic charge in a manner well known in the electrophotographic art, heating the recording element to soften the thermoplastic layer and to form a crazed image at the site of the electrodeposition of particles, and subsequently cooling the recording element to freeze the crazed image.

Referring now to FIG. 2 of the drawings, there is shown apparatus 10 for recording information on a recording element 12, having a transparent thermoplastic layer 14 of heat deformable material, in accordance with the improved method. The recording element 12 comprises a substrate 16, preferably of a transparent material, such as glass or "Mylar" plastic material. An electrode 18, in the form of a conductive layer of a transparent electrically conductive material, such as tin oxide, is coated on the substrate 16, and the thermoplastic layer 14 is coated on the electrode 18. An electrode 20 is disposed adjacent and parallel to, but slightly spaced from, the surface 22 of the recording element 12. The electrode 20 comprises a conductive electrode layer 24 which may be either a conductive coating of tin oxide on a transparent substrate, or a sheet of electrically conductive material. A photoconductive layer 28 of a photoconductor such as cadmium sulfide or cadmium selenide, for example, is coated on the electrode layer 24. The electrode 20 may also consist of a single sheet of a photoconductor, such as a sheet of selenium, for example.

The recording element 12 and the electrode 20 are disposed in a solution 26 within a transparent container 30, preferably glass, by any suitable means (not shown). The surface 22 of the recording element 12 is substantially parallel to the electrode 20 and is as close to it as possible without contacting it. A source of unidirectional voltage V is connected with its positive terminal to the electrode 20 and its negative terminal connected to the electrode 18 of the recording element 12.

The solution 26 may comprise either an electrolyte, such as copper sulfate, for example, containing sulfate anions and copper cations, or a colloidal solution of electrically charged particles, such as a liquid developer of the type used in electrophotography. In each case, the

charged particles will provide a current of particles under the influence of a suitable voltage V so that particles of one charge will move to an electrode of the opposite polarity.

Means are provided to control the current of charged particles between the electrodes 18 and 20 in the apparatus 10 in response to the information to be recorded. To this end, a lens system, represented by a lens 32, is disposed so as to project a light image, as from a photographic transparency 34, having light-transmitting portions representative of the information to be recorded, onto the photoconductive layer 28. A similar light image can also be projected onto the photoconductive layer 28 by a lens system 32a, from an opposite side of the electrode 20, if the electrode 20 has either a transparent substrate or is entirely photoconductive.

The improved method of recording information on the surface 22 of the recording element 12 with the apparatus 10 of FIG. 2 will now be described. If the solution 26 is an electrolyte, such as an electroplating solution of copper sulfate, for example, and if the resistance through 1 cm.² of the thermoplastic layer 14 is about 10^2 ohms, and the voltage V is such as to cause 10^{-1} amperes of current to flow, information can be recorded on the surface 22 in about 3×10^{-7} seconds. To do this, a light image of information, such as a light-transmitting portion of the transparency 34, is projected onto the photoconductive layer 28 while a voltage of about 10 volts, for example, is applied between the electrodes 18 and 20. Consequently, a current of copper ions flows through the solution 26 and copper is deposited on the surface 22 of the recording element 12. Since the resistance to the flow of the plating current is greatly reduced by the decreased resistivity produced between the light image projected onto the photoconductive layer 28 of the electrode 20 and the electrode 18, the copper electrodeposited onto the surface 22 of the recording element 12 is representative of the information to be recorded.

The quantity of particles, that is, copper, electrodeposited from the solution 26 onto the surface 22 under the conditions described, corresponds to an average thickness of at least 2×10^{-4} monolayer of copper. This quantity is substantially invisible to the naked eye. While 2×10^{-4} monolayer of deposited material is a lower limit of the quantity of particles that must be deposited on the surface 22 of the recording element 12 to provide a subsequent crazed image, the upper limit of electrodeposition may be substantially more. It is desirable, however, to deposit the material in as short a time as possible, but the amount of material deposited need not be visible to the naked eye.

The solution 26 can also be a colloidal solution of charged particles, such as electrically charged carbon particles in electrophotographic developing solutions well known in the electrophotographic art. When the solution 26 is colloidal, and the particles are positively charged, for example, the particles can be electrodeposited on the surface 22 of the recording element 12 with a suitable voltage V by the process of electrophoresis substantially as described for the electroplating of copper.

After recording the information by the electrodeposition of the particles on the surface 22 of the recording element 12, the recording element 12 can be removed from the solution 26 and stored until such time as it is desired to visualize the stored information. The stored information may be visualized by electrostatically charging the surface 22 with a uniform electrostatic charge and by heating the charged recording element 12, as by placing the recording element 12 on a hot plate or by directing a stream of hot air onto the surface 22, until the thermoplastic layer 14 deforms and produces a crazed, light-scattering image at the site where the particles were deposited. After crazing has occurred, the heat is removed from the recording element 12, and the crazed image of

the information remains frozen in the cooled recording element 12.

Referring now to FIG. 3, there is shown apparatus 10a somewhat similar to that of the apparatus 10 in FIG. 2, similar parts having the same reference number and modified parts being represented by a reference character consisting of both the original reference number and an added letter. The apparatus 10a is shown comprising a recording element 12a, having a substrate 16, and electrode 18, and a photoconductive thermoplastic layer 14a. Photoconductive thermoplastic layers, such as are included in the recording element 12a, are described in the aforementioned patents.

An electrode 20a comprises an electrically conductive metal disposed substantially parallel to, and slightly spaced from, the surface 22a of the recording element 12. The recording element 12a and the electrode 20a of the apparatus 10a in FIG. 3 are disposed in a solution 26 within a container 30, substantially as described for the recording element 12 and the electrode 20 of the apparatus 10 in FIG. 2.

Information, represented by one or more light-transmitting portions of the transparency 34 in FIG. 3 is recorded on the surface 22a of the recording element 12a as follows. In accordance with the improved method, a light image of the information is focused onto the photoconductive thermoplastic layer 14a of the recording element 12a by the lens system 32. Since the photoconductive thermoplastic layer 14a has a conductivity that varies directly with light intensity, its conductivity is markedly increased at the site of the projected light image thereon. Consequently, when a suitable voltage V (about 10 volts) is applied between the electrodes 18 and 20a, with the polarity shown in FIG. 3, a current of positively charged particles is caused to deposit at the site of the projected light image on the surface 22a.

The recording element 12a may now be removed from the solution 26, rinsed, dried, and stored until such time as it is desired to visualize the information thereon. A crazed image of the information is produced in the same manner described for producing such an image on the recording element 12 in FIG. 2. Thus, a visible crazed image can be produced by uniformly charging the surface 22a of the recording element 12a, as from a corona discharge device in a manner well known in the electro-photographic art, and subsequently heating the recording element 12a until the photoconductive thermoplastic layer 14a deforms and produces the crazed image. Upon cooling the recording element 12a, the crazed image remains fixed on the surface 22a and may be viewed either by the naked eye or through an appropriate optical projector.

Referring now to FIG. 4, there is shown apparatus 10b for producing information on the surface 22b of a recording element 12b. The recording element 12b has a substrate 16, an electrode 18 and a photoconductive thermoplastic layer 14a similar to those described for the recording element 12a in FIG. 3. In addition, the recording element 12b has a uniform film of particles, such as copper, for example, deposited on the surface of the photoconductive thermoplastic layer 14a in a quantity corresponding to a thickness of at least 2×10^{-4} monolayer, but substantially invisible to the naked eye. An electrode 20a is disposed parallel to, and slightly spaced from, the surface 22b of the recording element 12b by any suitable means (not shown) within a container 30 filled with a solution 26.

The voltage V (about 10 volts) applied between the electrodes 18 and 20a in the apparatus 10b is of a reverse polarity to the voltage V applied to the apparatus 10a in FIG. 3. Thus, in FIG. 4, information is recorded on the surface 22b of the recording element 12b by removing particles from a selected area of the film 36, leaving the remainder of the unremoved film 36 to define that information. Hence the information is recorded on the recording element 12b in the form of a negative recording, the

information recorded on the recording elements 12 and 12a in FIGS. 2 and 3, respectively, being considered in the form of a positive recording.

Information is recorded on the surface 22b of the recording element 12b in FIG. 4 in the following manner. In accordance with the improved method, a unidirectional voltage (about 10 volts) is applied with its positive terminal connected to the electrode 18 and its negative terminal connected to the electrode 20a. A light image of the information on the transparency 34, representative of the information to be recorded, is projected onto the photoconductive thermoplastic layer 14a by the lens system 32. The decreased resistivity, that is, the increased conductivity, at the site of the projected information causes particles to be removed from the conductive film 36, leaving particles of the film 36 on the remainder of the photoconductive thermoplastic layer 14a in the dark portions. The recording element 12b can now be stored for as long as desired, and the information may be visualized as crazed images, when desired, by the aforementioned operations of uniformly charging the surface 22b, heat deforming the photoconductive thermoplastic layer 14a, and cooling the recording element 12b. The information on the surface 22b is represented as a clear surface, defined by a crazed background resulting from the portion of the film 36 that has not been removed in the recording process.

The improved method is also applicable for continuously recording information on the surface of a moving web of a recording element. Apparatus 40, shown in FIG. 30, illustrates means for carrying out this embodiment of the improved method. A recording element 42 comprises a thermoplastic layer 14 on an electrically conductive backing 44, such as a metal foil or a relatively conductive paper, for example. A web of the recording element 42 is disposed for movement around a metal roller 46, in a direction indicated by the arrows 48 and 50, by any suitable means (not shown). The roller 46 is connected to a source of reference potential, such as ground, and functions as an electrode in a manner to be hereinafter described. The roller 46 is disposed in a solution 26 of charged particles within a container 52.

A plurality of parallel electrodes 53, 54, 55, 56 and 57 are disposed so that their tip ends are adjacent to, and very slightly spaced from, different areas of the surface 58 of the thermoplastic layer 14 of the recording element 42. The electrodes 53-57 are connected to a source 60 of unidirectional voltage through a plurality of relay operated switches 63-67, respectively, in an electrode selection matrix 68. The electrode selection matrix 68 is also connected to a source of information pulses, as through relay switches 63-67, whereby the source 60 of voltage may be applied selectively to one or more of the electrodes 53-57 in accordance with information pulses supplied to the matrix 68. Apparatus of the type for providing a source of information pulses to an electrode selection means useful in the improved method is described in detail in U.S. Pat. No. 3,060,432, issued to F. A. Schwertz, on Oct. 23, 1962, for "Electrostatic Recording of Information."

The negative terminal of the voltage source 60 is connected to the source of reference potential, ground, and its positive terminal is connected to the electrode matrix 68 for applying a selected voltage pulse to an appropriate one or more of the electrodes 53-57, in accordance with information pulses.

In operation, the web of the recording element 42 is moved in contact with, and around, the roller 46 within the solution 26 of charged particles. In response to the information pulses, voltage pulses are applied between one or more of the electrodes 53-57 and the roller 46, and the charged particles of the solution 26 are electro-deposited by the resulting current. Particles from the solution 26 are deposited onto the surface 58 of the recording element 42 substantially adjacent the tip ends of the electrodes 53-57 because the electrical resistance to the current flow of the charged particles is least in the shortest

distances between the tip ends of the electrodes 53-57 and the (electrode) roller 46.

The recorded information, that is, the electrodeposited particles on the surface 58 of the recording element 42, can be stored on the recording element 42 for as long a period as desired, and the information may be visualized, when desired, by uniformly charging the surface 58 with an electrostatic charge, and heat deforming the thermoplastic layer 14 until crazing occurs at the sites of the recorded information. The recorded information appears 10 as light-scattering, crazed images which can be visualized with the naked eye.

Thus, there has been described an improved method of recording information on a recording member having a thermoplastic layer. While the information on the recording member has been defined by particles, either deposited onto the thermoplastic layer or removed therefrom, it is understood that the quantity of the material deposited or removed is a function of the current carried by the charged particles, which in turn, is a function of the intensity of the light of the information image and/or the amplitude of the information pulses. Consequently, the amount of deposited material can be varied by modulating the intensity of the light information and/or the amplitude of the information pulses. Hence, crazed images of varying tone are produced by information containing modulated light images or modulated information pulses.

What is claimed is:

1. A method of recording information on the surface of a recording element comprising a layer of deformable thermoplastic material, said method comprising disposing said surface in a solution comprising electrically charged particles, electrodepositing on a selected area of said surface, representative of said information, particles from 35 said solution in a quantity corresponding to an average thickness of at least 2×10^{-4} monolayer of deposited particles, but substantially invisible to the naked eye, removing said surface from said solution, 40 charging said surface with a uniform electrostatic charge, and heating said recording element to a temperature at which said thermoplastic material deforms, whereby to provide a visible crazed image at the site of said deposited particles on said surface.

2. A method of recording as described in claim 1, wherein said layer of thermoplastic material is disposed on one electrode, and said electrodepositing on said surface comprises disposing another electrode in said solution adjacent said layer of thermoplastic material, applying a voltage between said electrodes to provide a current of said

charged particles through said solution, and selectively controlling the flow of the resulting current through said solution to electrodeposit said particles from said solution only in said selected area of said surface.

3. A method of recording as described in claim 2, wherein

said layer of thermoplastic material is photoconductive and said controlling said current comprises projecting a light image of said information onto said layer of photoconductive thermoplastic material, whereby to vary the resistance selectively between portions of said electrodes and to electrodeposit said particles on said selected area of said surface.

4. A method of recording as described in claim 2, wherein at least one of said electrodes is transparent and comprises a photoconductive layer thereon, and

said controlling said current comprises applying pulses of light image of said information onto said photoconductive layer, whereby to vary the resistance selectively between said electrodes and to electrodeposit said particles selectively on said selected area of said surface.

5. A method of recording as described in claim 2, wherein

said other electrode comprises a plurality of smaller electrodes, each smaller than said one electrode, and said controlling said current comprises applying pulses representative of said information between said one electrode and selected ones of said smaller electrodes, whereby to cause a migration of said particles only to said selected area of said surface, representative of said information.
